UNITED STATES PATENT OFFICE

2,545,012

KEY CASE

Benjamin Wohl, Lancaster, Pa.

Application March 5, 1948, Serial No. 13,129

2 Claims. (CL. 150—40)

1

This invention appertains to novel and useful improvements in devices for supporting and maintaining keys in an orderly fashion.

An object of this invention is to maintain a plurality of keys in segregated series within protective housings, forming a single unit.

Another object of this invention is to supply a key case within a key case forming a single unit.

Another object of this invention is to maintain an inner strip foldable within an outer strip, the outer strip also being foldable around said inner strip and supply means for maintaining keys on opposite marginal edges of the inner strip, the key retaining means being on opposed or opposite surfaces.

Another object of this invention is to supply an improved combination key case, provided with means whereby a series of keys may be segregated within a single device.

Another object of this invention is to provide an extremely simplified device of the nature to be described capable of maintaining an abnormally large numbers of keys in a single, compact unit.

Ancillary objects and features of novelty will become apparent to those skilled in the art, in following the description of the preferred form of the invention, illustrated in the accompanying drawings, wherein:

Figure 1 is a perspective view of the preferred form of the invention;

Figure 2 is a perspective view of the invention shown in Figure 1, illustrating the same in the open position;

Figure 3 is a fragmentary perspective view of the device illustrated in Figure 2, the inner strip being folded back to illustrate details of construction;

Figure 4 is a sectional view taken substantially on the line 4—4 of Figure 1 and in the direction of the arrows;

Figure 5 is a plan view illustrating a pattern piece or strip of material utilized in association with the present invention, and

Figure 6 is a sectional view taken on the line 6—6 of Figure 3 and in the direction of the arrows.

This invention has been developed for the purposes set forth in the preceding paragraphs as well as other subsidiary purposes. The preferred materials of construction are leather however, other materials may be utilized if it is found desirable. Of course, the key retaining means may be made of metal or commercial plastic, likewise the fastening means.

An outer foldable strip 10 is substantially rectangular in cross section, deviating from the rectangle at one edge 12 which has a projecting portion. Complementary snap fastening elements

14 and 16 respectively are provided on the said outer foldable strip adjacent opposed edges 12 and 18 respectively thereof.

If it is found desirable a row of stitching 20 may be supplied at the marginal edge of the outer strip 10 for trim purposes. Of course, other expedients such as placing a binding about the edges of the strip 10 may be resorted to, if a more expensive article is desired. Further, ornamental markings may be supplied as found desirable.

A second or inner strip 24 of substantially T-shaped configuration is supplied and is attached at one edge 26 to the edge 28 of said outer strip 10. Conventional stitches 30 may be utilized in making this connection.

If found expedient, the inner strip and outer strip may be formed of a single piece construction thereby eliminating the connection at the edges 26 and 28.

The said inner strip 24 is foldable and attaching means, preferably a snap fastener 32 and its complement 33, is provided adjacent opposed edges of the said T-shaped member 24 for maintaining this inner member in the closed position.

Secured adjacent the marginal edges 26 and 34 of the said inner or T-shaped member 24 is means for maintaining keys. This means includes identical constructions including a plate 36 riveted by utility of the conventional rivet elements 38, to the said inner strip 24. A pin 40 extends along the longitudinal edge of the said plate 36 and is provided with a plurality of pivoted members 42 which are formed in a series.

Resilient clips 44 are attached to the individual keepers, which are spaced by the utility of the collars 46. (See Figure 2.)

It is noted from inspection of Figure 2 that the opposed key retaining means are supplied on opposite surfaces of the said strip 24 thereby permitting keys to be positioned within the case in a substantially longitudinally aligned manner.

Inspection of Figures 2 and 3 illustrate the segregation which is possible by utility of the present invention and also illustrates the cantilever fashion by which the interior strip is associated with the outer strip 10.

From the foregoing it is believed that a clear understanding of the invention is readily ascertained. Therefore, a more lengthy description is deemed unnecessary.

It is apparent however, that certain variations including changes as to size and shape may be made without departing from the spirit of the invention. Therefore, limitation is sought only in accordance with the scope of the following claims.

Having described the invention, what is claimed as new is:

1. A key case comprising an outer foldable

strip having fastening means adjacent opposite edges thereof to releasably retain said outer strip in a folded condition, an inner foldable substantially T-shaped strip having a central section and a pair of laterally projecting leaves, a key retaining device secured to said central section between said leaves, fastening means carried by said leaves releasably retaining said leaves in the folded condition covering at least a part of said key retaining device, and means fastening said central section to said outer strip.

2. A key case comprising an outer foldable strip having fastening means adjacent opposite edges thereof to releasably retain said outer strip in a folded condition, an inner foldable substantially T-shaped strip having a central section and a pair of laterally projecting leaves, a key retaining device secured to said central section between said leaves, fastening means carried by said leaves releasably retaining said leaves in the folded condition covering at least a part of said key retaining device, means fastening said cen-

tral section to said outer strip, and a second key retaining device secured to the surface of said central section remote from the surface of said central section contacting said outer strip.

BENJAMIN WOHL.
